BRASSIÈRE

Elvira C. McKeefrey, New York, N. Y., assignor to Model Brassiere Corp., Brooklyn, N. Y.

Application July 18, 1949, Serial No. 3,977

Term of patent 7 years

(Cl. D20—4)

To all whom it may concern:

Be it known that I, Elvira C. McKeefrey, a citizen of the United States of America and resident of the county of Kings, city and State of New York, have invented a new, original, and ornamental Design for a Brassière, of which the following is a specification, reference being had to the accompanying drawing forming a part thereof, in which:

Fig. 1 is a front view of a brassière showing my new design with parts thereof being shown broken away for convenience of illustration.

Fig. 2 is a rear view thereof.

I claim:

The ornamental design for a brassière, as shown and described.

ELVIRA C. MCKEEFREY.
